UNITED STATES PATENT OFFICE.

EDWARD W. WISCH AND WALTER J. WISCH, OF BALTIMORE, MARYLAND, ASSIGNEES
TO THEMSELVES, SIDNEY C. VINCENT, AND FREDERICK C. VOLKMAN, BOTH OF
BALTIMORE, MARYLAND.

HAND-OPERATED TOILET FAN.

Application filed May 11, 1921. Serial No. 468,466.

To all whom it may concern:

Be it known that we, EDWARD W. WISCH and WALTER J. WISCH, citizens of the United States, residing at Baltimore, in the State of Maryland, have invented certain new and useful Improvements in Hand-Operated Toilet Fans, of which the following is a specification.

This invention relates to improvements in hand operated fans.

The class of fans to which the invention belongs is that in which a fan shaft is mounted in suitable bearings in an appropriate casing, and through a suitable gear train within the casing, is given a fast rotary motion, by the manipulation of a reciprocating plunger.

In our application filed simultaneously herewith, we have shown and described a fan mechanism of this character, in which application stress is particularly laid upon the mechanism for clutching or locking the main driving gear to its shaft so that it will engage and move with the shaft in one direction, whereas in the present instance, the improvement resides in the manner of attaching the fan blades to the fan shaft.

The object of the present invention is to so attach the blades to the fan shaft that they will be thrown automatically to their respective open positions upon the manipulation of the actuating plunger, and remain in open and properly spaced position so long as the fan shaft is being rotated, but when the fan shaft stops the wings will automatically, or of their own accord, drop back to folded position, thus obviating the necessity in the first instance of opening the wings to their properly relative or three-way position, and adjusting or holding them in such position prior to their rotation.

In the ordinary constructions, the wings have to be separately brought to proper open position and there held either by a clamp or by reason of some peculiar formation of the inner ends of the fan blades. They also have to be folded manually for packing the fan, or for putting it into the pocket or other receptacle, when not in use. Unless the fan blades are properly spaced and of equidistance apart, they will cause a very awkward and uncomfortable vibration when the fan is in motion. Hence the necessity and advantage of the present con-

struction in which the wings are forced to their properly spaced open position, and with the construction there is the advantage of not having to manually fold the wings when the fan is stopped.

In the drawings illustrating the invention—

Fig. 1 is a perspective view of the fan.

Fig. 2 is a face view.

Fig. 3 is a detailed broken view of one of the inner ends of the fan blades showing the form of washer used to retain the inner ends of the blades in proper position relative to each other.

Fig. 4 is a longitudinal section of the casing and some of the parts contained therein, as well as a section of the boss which is mounted upon the fan shaft, and

Fig. 5 is a face view of the wings in folded position.

Since the invention of this application does not reside in the arrangement of the internal parts of the fan, they will be but generally described.

Referring to the drawings, the numeral 1 designates a casing of any suitable shape, and of any suitable material, but preferably round, as shown, and preferably made of thin metal enamelled, japanned or lacquered, as fancy may dictate. Mounted in suitable bearings in the casing just off center is the main driving shaft 2 which carries a pinion 3, tight upon the shaft. This pinion is engaged by the rack 4 of a plunger 5 which is provided on the outside of the casing with a thumb or finger rest 6. A bracket 7 is provided on the inside of the casing, which has in it a kerf 8 to receive the lower end of the plunger. Rigidly attached to the lower end of the plunger is a bracket 9 to which is attached at one end a spiral spring 10, and the other end of the spring being attached to an eye 11 on the inner periphery of the casing.

Mounted on the shaft 2 to one side of the pinion is a boss 12, grooved as indicated at 13 for the reception of a washer 14, and the numeral 15 designates the main driving gear which surrounds the boss and rests against the flange 16 formed at one side of the boss. Interposed between the washer 14 and the face of the wheel 15 is a very thin washer 17 that rests very lightly against the driving gear and resists its rotation only.

sufficiently to prevent lost motion. The mechanism is such that the driving gear will be locked to the boss only when the boss is turned in one direction. The driving gear 5 meshes with a pinion 18 carried by the fan shaft 19 journalled in suitable bearings in the lower part of the casing, the front end of the shaft being reduced to form a stem 20 embraced by the boss 21 provided at its outer end with a flange 22 of sufficient area to cover a suitable part of the lower end of the outer fan blade. The boss is further provided at its inner end with an annular groove 23 for the reception of a washer 24, 10 and interposed between the flange 22 and the washer 24 are the inner ends of the fan blades, there being three of such blades, an outer blade 25, an intermediate blade 26, and a lower blade 27. Two of these blades are 15 mounted loosely between the flange 22 and the washer 24, that is to say, they are so mounted so as to be readily movable, one upon the other, and the outer blade 25 is pinned to the flange 22 by a pin 28 so that 20 its outer blade must move with the boss whenever the fan shaft is rotated. The wing 25 is provided at its inner end with a projection 29 adapted to engage with an outwardly extending lug 30 upon the intermediate wing, and the wing 25 is further 25 provided at its edge with a lug 31 similar to the lug 30 to engage the edge of the underneath or lower wing 27 when the fan blades are in extended or opened position. 30 Two of the wings are, as stated, loosely mounted on the boss, that is to say, they can move quite freely thereon. Normally the wings are in the folded or inoperative position, shown in Figure 5, but when the 35 plunger is depressed, through the train of gearing in the casing, the fan shaft with its boss 21 will be rapidly rotated, and the blade 25 being compelled by the pin connection with the boss will be carried quickly 40 away from its normal position, leaving for the moment the other two blades, but when the fan blade 25 has been carried for a short distance, the projection 29 thereon will engage the lug 30 on the fan blade 26, and 45 thus lock these two blades for simultaneous rotation, and simultaneously, the lug 31 will engage the edge of the blade 27 at which point the blades will be properly spaced apart, and the fan established for operation, 50 and obviously, further rapid rotation of the fan holds all of the blades in the position shown in Figures 1 and 2, but when the rotation of the fan shaft ceases, the blades all fall to normal or folded position, or the position shown in Figure 5.

In operation the plunger is depressed against the resistance of the spring 10, and by reason of the engagement of its rack with the pinion 3, the driving shaft will be rapidly 55 rotated, and as before suggested, in the

outward movement of the plunger, the driving wheel will be locked to the boss, and the gear being in mesh with the pinion 18, the fan shaft will be rapidly rotated, but upon the upward movement of the plunger, 70 the clutch is released under which condition, the driving wheel may rotate independently of the boss, and as mentioned above, the rapid rotation of the fan shaft will cause the fan blades to instantly assume, coming 75 from folded position, the open or operative position, in which position they will be held by their various engagements, which have been indicated.

The washers 14 and 24 are preferably 80 similar in construction, and as best shown in Figure 3, they are provided with an enlarged circular opening 32, which merges into a smaller opening 33 which is formed in the central part of the washer, and which 85 part rests in the annular groove in the boss, to which it is applied to set the washers in place, it is only necessary to project the end of the boss through the larger opening and then slide the washer laterally until the edge 90 of its smaller opening seats in the groove in the boss.

Claims:

1. In a fan of the character described, the combination with a fan shaft, and means for driving said shaft, a series of fan blades carried by the shaft, one of the blades having positive connection with the shaft, and a plurality of means carried by the positively connected blade adapted to cooperate 105 with the remaining blades whereby each of the remaining blades is forced by said means to open or unfolded position and carried with the fixed blade upon the rotation of the fan shaft.

2. In a fan of the character described, in combination, a suitable casing, a fan shaft journalled in said casing, means for imparting continuous rotation of the fan shaft, a series of fan blades mounted upon the shaft, 110 one of which is fixed to the shaft, a projection at the inner end of the fixed blade and a lug carried by another blade adapted to be engaged by said projection whereby the blade so engaged will rotate with the fixed blade, and a lug at the edge of the fixed blade adapted to engage another blade whereby when all of the projections and lugs are in engagement, the blades will be compelled to 115 rotate together in properly spaced open position.

3. In a fan of the character described, in combination, a suitable casing, a fan shaft journalled in said casing, means for imparting a rotary motion to the fan shaft, a series 120 of fan blades carried by the shaft, the outer one of which has positive connection with the shaft, a projection at the inner end of the outer blade, a lug carried by the intermediate blade adapted to be engaged by said 125

projection, a lug carried by the outer blade adapted to engage the edge of the lowermost blade, whereby all of the blades when such engagement is affected are compelled to rotate together in properly spaced open position.

4. In a fan of the character described, in combination, a suitable casing, a fan shaft journalled in said casing and means for imparting rotary motion to the fan shaft, three fan blades carried by the fan shaft outside the casing, the outer blade being provided with a projection at its inner end and an inwardly extending lug on one edge thereof, a lug carried by the intermediate blade adapted to be engaged by the projection on the outer blade, whereby when said lugs and projections are so engaged, all of the wings are caused to be locked together in properly spaced open position for simultaneous rotation.

5. In a fan of the character described, in combination, a suitable casing, a fan shaft journalled in the casing, means for imparting rotary motion to said shaft, a 25 boss carried by the fan shaft outside the casing, a series of wings mounted on the boss, one of which is pinned to the boss so that the wing is caused to rotate with the boss, a plurality of means 30 equally spaced on opposite sides of said wing carried by the outer wing, each of said means cooperating with a respective other wing whereby when they are brought to opened or unfolded position, all of the wings 35 will be caused to rotate together in properly spaced position.
